[57] ABSTRACT

The vacuum line between the carburetor spark port and the engine distributor breaker plate servo actuator includes an air bleed valve that is normally closed to permit normal advance of the engine timing as a function of spark port vacuum changes, but is opened by a servo actuated directly by the carburetor accelerator pump linkage during vehicle accelerations to bleed air to the distributor servo to condition the timing for retarded operation.

ACCELERATOR PUMP CONTROLLED ENGINE SPARK TIMING

This invention relates, in general, to a device that aids in the reduction of exhaust emission pollutants from an internal combustion engine. More specifically, it relates to a mechanical spark timing control device that eliminates carburetor spark port vacuum to the distributor during vehicle accelerations in response to operation of the carburetor accelerator pump.

Most present day motor vehicles have some sort of a vacuum servo automatically controlling the advance or retard setting of the engine distributor breaker plate as a function of carburetor spark port vacuum to provide good engine performance as well as fuel economy during the different operating conditions of the engine. These vacuum servos, in their simplest forms, generally consist of a housing divided into atmospheric pressure and vacuum chambers by a flexible diaphragm connected to the distributor breaker plate. The diaphragm and breaker plate are normally spring biased to the lowest advance or retard spark timing setting, and carburetor spark port vacuum normally urges the diaphragm in a spark timing advance direction upon opening of the carburetor throttle valve in an engine speed increasing direction.

With the above construction, vehicle accelerations from an idle speed condition cause vacuum at the carburetor spark port to act on the one side of the servo diaphragm to immediately move the distributor breaker plate to an advanced setting. This provides a longer burning time for the fuel mixture before the optimum top or near top dead center position of the piston is attained, generally providing the most desirable operation. However, this longer time permits a build-up to higher combustion temperatures and pressures, which is undesirable insofar as the production of oxides of nitrogen and other undesirable elements are concerned.

It will be seen, therefore, that the conventional spark timing control systems may provide good performance and fuel economy, but do not necessarily minimize the output of undesirable exhaust gas elements.

Therefore, it is a primary object of the invention to provide an engine spark timing device that has the advantages of the conventional spark timing control system while minimizing the disadvantages; by providing a device that retards the spark timing during vehicle accelerations, to decrease NO_x output, while extending burning of the mixture into the exhaust system to reduce the amount of exhaust gas emission of other undesirable elements.

It is another object of the invention to provide an engine spark timing control system including a device that meets the requirements set out immediately above, by including an accelerator pump linkage actuated atmospheric pressure air bleed in the vacuum line to the distributor servo to bleed spark port vacuum during vehicle accelerations.

Other objects, features and advantages of the invention will become more apparent upon reference to the succeeding detailed description thereof, and to the drawing illustrating a preferred embodiment thereof; wherein the FIGURE illustrates schematically a cross-sectional view of an engine spark timing control apparatus embodying the invention.

The FIGURE shows, schematically, only those portions of an internal combustion engine that are normally associated with the engine distributor spark timing setting control; such as, for example, a carburetor 10, a distributor breaker plate 12, a vacuum servo 14 to control the movement of breaker plate 12, and a line 16 connected between the carburetor and vacuum servo to automatically change the engine spark timing setting as a function of changes in engine vacuum spark port setting.

More specifically, carburetor 10 is shown as being of the downdraft type having the usual air-fuel induction passage 18 with an atmospheric air inlet 20 at one end and connected to the engine intake manifold 22 at the opposite end. Passage 18 contains the usual fixed area venturi 24 and a throttle valve 26. The latter is rotatably mounted on a part of the carburetor body across passage 18 in a manner to control the flow of air-fuel mixture into the intake manifold. Fuel would be inducted in the usual manner from a nozzle, not shown, projecting into or adjacent venturi 24, in a known manner.

Throttle valve 26 is shown in its engine idle speed position essentially closing induction passage 18, and is rotatable to a nearly vertical position essentially unblocking passage 18. A spark port 28 is provided at a joint just above the idle position of throttle valve 26, to be traversed by the throttle valve during its opening or part throttle movements. This will change the vacuum level in spark port 28 as a function of the rotative position of the throttle valve, the spark port reflecting essentially atmospheric pressure in the air inlet 20 upon closure of the throttle valve.

As stated previously, the distributor, not shown, includes a breaker plate 12 that is pivotally mounted at 30 on a stationary portion of the distributor, and movable with respect to cam 32. The latter has six peaks 34 corresponding to the number of engine cylinders. Each peak cooperates with the follower 36 of a breaker point set 38 to make and break the spark connection in a known manner for each one-sixth, in this case, rotation of cam 32. Pivotal movement of breaker plate 12 in a counterclockwise spark retard setting direction, or in a clockwise spark advance setting, is provided by an actuator 40 slidably extending from vacuum servo 14.

Servo 14 may be of a conventional construction. It has a hollow housing 42 whose interior is divided into an atmospheric pressure chamber 44 and a vacuum chamber 46 by an annular flexible diaphragm 48. The diaphragm is fixedly secured to actuator 40, and is biased in a rightward retard direction by a compression spring 50. Chamber 44 has an atmospheric or ambient pressure vent, not shown, while the chamber 46 is connected to line 16.

During engine-off and other operating conditions to be described, atmospheric pressure exists on both sides of the diaphragm 48, permitting spring 50 to force the actuator 40 to the lowest advance or a retard setting position. Application of vacuum to chamber 46 moves diaphragm 48 and actuator 40 toward the left to an engine spark timing advance position, by degree, as a function of the change in vacuum level.

Turning now to the invention, an air bleed device 52 is located in line 16 between servo 14 and spark port 28. The device 52 includes a valve body 54 defining a

three passage fluid chamber 56. Passage 58 is a vent and connects to atmospheric pressure. Passage 60 is connected to servo line 16, and passage 62 is connected to spark port 28.

A valve member 64 is sealingly mounted to slide through chamber 56, as shown. It includes a main cylindrical body portion 66, a reduced diameter end actuator portion 68, and a conical intermediate portion 70. The conical portion 70 is adapted to seat at times against a matingly formed portion 72 of body 54 to cut off vacuum flow from spark port 28 to servo chamber 46. Simultaneously, the downward movement of valve 64 engages the end 68 with a flexible reed-like valve 74 to bend open the same and connect line 60 to atmospheric pressure. The valve 74 is fixedly riveted or otherwise mounted at one end to body 54, as shown.

The upper end of valve 64 is fixed to an annular flexible diaphragm 76 that forms one wall of an air chamber 78. The opposite wall of the chamber is defined by a second annular flexible diaphragm 80 that is sealingly mounted across the center of a hollow housing 82. An actuating lever 84 is fixedly secured to diaphragm 80, and slidably projects through a boss 83 in the housing, as shown. Air leaking along the shaft maintains chamber 86 at atmospheric pressure.

The actuator 84 forms an integral part of the conventional carburetor accelerator pump linkage, not shown. As a result, it moves vertically concurrently with movement of the throttle linkage to open throttle valve 26 during vehicle accelerations, in a known manner. Lever 84 will be returned to the position shown by the conventional throttle return spring, not shown, upon release of the vehicle accelerator pedal by the operator.

Completing the construction, chamber 78 includes an air bleed consisting of an orificed passage 88 that slowly bleeds the air pressure in chamber 78 at times, and at other times restores chamber 78 to an atmospheric pressure level.

In operation, at engine start up, both chambers 78 and 86 are at ambient or atmospheric pressure as are both sides of the servo 14. Accordingly, a spring 90, seated between housing 54 and diaphragm 76, has biased valve 64 upwardly to permit bleed valve 74 to close, and the distributor breaker plate 12 has been rotated by spring 50 to its maximum retard spark timing position.

The condition described above also is applicable during engine idle speed operation, in that the pressure in spark port 28 then is essentially atmospheric, or that in the air inlet portion 20.

Assume now that the vehicle accelerates lightly, throttle valve 26 rotating counterclockwise. Immediately spark port 28 is subject to vacuum in the intake manifold 22. Though low, vacuum acting through chamber 56 normally would permit the atmospheric pressure in chamber 44 to compress spring 50 and move the breaker plate 12 towards a spark timing advance position. However, movement of the throttle valve linkage simultaneously moves the accelerator pump lever 84. This does two things. First, movement of diaphragm 80 downwardly pressurizes chamber 78. Secondly, diaphragm 76 is moved downwardly against spring 90 to seat valve 64 to block line 62 while simultaneously opening bleed valve 74. This maintains

passage 60 at atmospheric pressure and, therefore, servo chamber 46. Accordingly, breaker plate 12 is maintained in the maximum engine spark retard position.

As the acceleration of the vehicle proceeds, the leakage of air pressure from chamber 78 through bleed 88 permits the spring 90 to move diaphragm 76 upwardly. When the pressure in chamber 78 has reduced, valve 64 will return to its original position shown. This effects a slow closing of air bleed valve 74 with a consequential slow buildup of vacuum in line 60 from the spark port 28. When the pressure in chamber 78 is reduced, the spark timing plate 12 will assume the advance position dictated by the vacuum in line 62.

If, during the accelerating operation, the throttle valve is suddenly moved to a closed position, indicating a decelerating operation, the accelerating pump lever 84 is returned to the full line position by spring means not shown. This decays the pressure in chamber 88, and permits spring 90 to move diaphragm 76 upwardly. This upward movement unseats valve 64 and closes bleed valve 74. However, since essentially atmospheric pressure is prevalent at spark port 28, the breaker plate 12 will be maintained at a maximum retard setting.

From the above, it will be seen that the invention conditions the engine spark timing for a maximum retard setting during engine accelerating operations and maintains that retard setting during vehicle decelerations. It will also be seen that the device permits normal advance of the spark timing.

I claim:

1. A motor vehicle engine spark timing control system comprising, an engine carburetor having an induction passage containing a spark port located above the idle speed position of a throttle valve controlling flow through the passage and subject to the depression in the carburetor as a function of the movement of the throttle valve from its idle speed position, an engine distributor having a breaker plate pivotally movable in opposite directions to advance and retard the spark timing, spark port connected vacuum controlled servo means connected to said breaker plate for moving the same normally solely as a function of spark port vacuum changes, and control means between said spark port and servo means to control the application of vacuum from said spark port to said servo means, said control means including conduit means connecting the vacuum at said spark port to said servo means for effecting variable movement of said breaker plate from a maximum retard setting at closed throttle valve idle speed position to a maximum advance setting at high spark port off-idle vacuum levels, and an air bleed means openable in response to vehicle acceleration demand independently of spark port vacuum level to momentarily bleed air to said servo means to position said breaker plate at a maximum retard setting, said air bleed means including a normally closed atmospheric pressure vent in said conduit means, and a valve movable through said conduit means to block the fluid signal from said spark port while simultaneously opening said vent to connect said servo means to atmospheric pressure.

2. A control system as in claim 1, including a second movable valve normally closing said vent and movable by said first mentioned valve to open said vent.

3. A control system as in claim 2, said second valve comprising a flat flexible reed-like valve bendable by said first mentioned valve.

4. A control system as in claim 1, including manually operable means operably connected to said valve for moving the same in a direction to open said vent, and spring means biasing said valve in the opposite direction.

5. A control system as in claim 4, said carburetor including an operator movable accelerator pump linkage, said manually operable means comprising link means adapted to be operably connected to the pump linkage so as to be movable concurrently therewith upon movement of said linkage by the vehicle operator.

6. A control system as in claim 4, including second servo means between said manually operable means and said valve for operably moving said valve to open said vent.

7. A control system as in claim 6, said second servo means including a hollow housing, a pair of flexible diaphragms in said housing defining a fluid pressure chamber therebetween, a second air vent connected to said chamber, a flow restrictor in said second air vent, and means connecting one of said diaphragms to said valve and the other of said pair of diaphragms to said manually operable means whereby movement of said latter means effects a movement of said valve to open said first mentioned vent, said flow restrictor defining a time delay bleed of pressure from said chamber for the return movement of said first diaphragm and valve to effect closing of said first mentioned vent.

8. A control system as in claim 7, said air bleed

means comprising a flat reed-like flexible valve normally closing said first mentioned vent and bendable by said first mentioned valve upon engagement thereby to a position opening said latter vent.

9. A spark timing control system comprising, an engine carburetor having an induction passage containing a spark port located above the idle speed position of a throttle valve controlling flow through the passage and subject to the depression in the carburetor as a function of the movement of the throttle valve from its idle speed position, an engine distributor having a breaker plate pivotally movable in opposite directions to advance and retard the spark timing, vacuum controlled servo means connected to said breaker plate for moving the same, and flow rate control means between said spark port and servo means to control the rate of change of application of vacuum from said spark port to said servo means, said control means including conduit means connecting the vacuum at said spark port to said servo means for normally effecting variable movement of said breaker plate from a maximum retard setting at closed throttle valve idle speed position to a maximum advance setting at high spark port off-idle vacuum levels solely as a function of spark port vacuum changes, and an air bleed means openable independently of the spark port vacuum by and in response to movement of the accelerator pump linkage of said carburetor to bleed air to said servo means during accelerative modes of operation of said vehicle while simultaneously shutting off a portion of the conduit means containing the spark port vacuum.
